GRADER OR SIZER

Fred Hodecker, Redmond, Oreg.

Application June 21, 1943, Serial No. 491,648

6 Claims. (Cl. 209—106)

This invention relates broadly to "sizers" or graders which are employed for sorting or grading fruits and vegetables as to size. More particularly, this invention relates to "sizers" or graders for potatoes, and, since the device is employed chiefly in connection with the grading of potatoes, it will be described as a potato "sizer," although it is to be understood to be adapted for similar use with other vegetables or fruits which require like grading as to size, and with various other products and materials.

In order to comply with market specifications and to meet requirements for definite price schedules it is necessary to sort potatoes carefully according to their size. In the device of the present invention the largest or oversize potatoes, which require no definite minimum size, are first separated from the pack. Then the remainder of the pack is segregated into successively varying sizes, each particular size being segregated separately as desired.

In my grader, as in other similar devices, the sorting out of the different sizes is done by means of rotating rollers which are so arranged as to allow the potatoes of smaller size than the size being sorted by the particular row of rollers to pass down between the rollers. One of the difficulties in general with such graders or "sizers" is the danger that potatoes which are slightly larger than the proper size to pass between the rollers will nevertheless attempt to go between them and become squeezed or wedged in so doing.

One of the objects of this invention is to provide an improved "sizer" in which such danger of the potatoes attempting to pass between the rollers, when they are not small enough to be able to do so without being squeezed by the rollers, will be eliminated.

Another object of this invention is to provide an improved arrangement of "splitting" rollers in order first to separate from the pack the potatoes to be classified as oversize, before the subsequent grading of the remaining potatoes, and to provide for suitable adjustment of such "splitting" rollers.

A further object of this invention is to provide simple means for combining or mixing potatoes of two or more sizes to comply with requirements when fewer separate grades are needed.

These and other incidental objects I have been able to accomplish by constructing my grader or "sizer" in the manner hereinafter briefly described. In the description reference is made to the accompanying more or less diagrammatic drawings, in which:

Figure 1 is a diagrammatic illustration of the entire grader and of its mode of operation;

Figure 2 is a fragmentary sectional side elevation of the adjusting mechanism and mounting for one end of the first row of rollers or "splitting" rollers, the section corresponding to the line 2—2 of Figure 3;

Figure 3 is a fragmentary sectional plan of the same end mounting of the "splitting" rollers, 10 showing also the driving means for the rollers, the plan corresponding to line 3—3 of Figure 2;

Figure 4 is a fragmentary plan view of one row of the sizing rollers, of which there are a plurality of rows in the grader;

15 Figure 5 is a diagrammatic illustration of the manner in which the "splitting" rollers are driven;

Figure 6 is a diagrammatic illustration of a modified form of my grader or "sizer" and its 20 mode of operation; and

Figure 7 is a diagrammatic end view of the modified device of Figure 6.

As indicated in Figure 1, my grader includes a plurality of rows or tiers of rollers 10, 19, 24, 26 25 and 27 arranged in consecutive spaced horizontal relation one below the other. Each row of rollers discharges on to a separate conveyor. The number of rows is determined by the number of grades or sizes of potatoes, or other produce, customarily required, but provision is also made for combining the discharges from two or more consecutive rows of rollers should fewer grades or sizes be required for the particular sorting.

The top row or tier 10 I designate as "splitting" 35 rollers. The purpose of the "splitting" rollers in this row is to separate and remove the oversize potatoes, which are too large for any exact sizing even under minimum requirements. These oversize potatoes are removed from the rest of the

40 pack, so as to permit the balance of the pack to be sorted and sized separately. This row of "splitting" rollers includes one set of spaced rollers 10', journaled at each end in bearings 11 (see Figure 2) which bearings are secured to suitable longitudinal members 12 of the grader frame,

45 and another set of rollers 13 journaled at each end in bearings 14 which are secured to movable side plates 15 mounted so as to slide longitudinally between the frame members 12. As shown in Figures 1 and 2, the rollers 10' and 13 are arranged alternately. The positioning of the side plates 15, and consequently the positioning of the 50 movable rollers 13 with respect to the stationary rollers 10', is done by means of a pair of hand wheels 17, one at each side, which are secured

55 in Figures 1 and 2, the rollers 10' and 13 are arranged alternately. The positioning of the side plates 15, and consequently the positioning of the movable rollers 13 with respect to the stationary rollers 10', is done by means of a pair of hand wheels 17, one at each side, which are secured

to adjusting screws 18. Ordinarily the rollers 13 will be so positioned that there will be a relatively large space 18 between each roller 13 and the preceding roller 10' (reading from left to right in Figure 1) and a relatively small space 18' between such roller 13 and the next succeeding roller 10'. The position of the rollers 13 is adjusted so that the spaces 18 will be of the proper size to permit all the potatoes which are to be graded further to pass through these spaces while not being large enough to accommodate the oversize potatoes. In this way the oversize potatoes are separated at the outset from the rest of the pack, and the rest of the pack is then subsequently graded.

The rollers 10' are driven in unison in clockwise direction (as viewed in Figure 1) preferably through the medium of suitable sprockets 39 (Figures 3 and 5) secured to one end of the roller shafts. These sprockets 39 are engaged by an endless sprocket chain 37 driven by a suitable sprocket drive wheel 38 connected to a source of power (not shown). The rollers 13 are also driven in unison in the same direction but at a greater rate of speed than the rollers 10'. Rollers 13 are similarly driven through the medium of sprockets 36, sprocket chain 40 and suitable driving means 41. The driving of the adjustable rollers 13 at a speed different from and faster than that of the fixed rollers 10' is an important feature in my improved grader. Any potatoes which are only very slightly oversize ordinarily might have a tendency to become wedged or squeezed in the large space 18, but the fact that roller 13 will be rotating at a faster rate of speed than the preceding roller 10' and that both rollers are rotating in the same direction will prevent any wedging or squeezing of such potato in this space 18 and will cause the oversize potato to be moved forward over the space and over the roller 13. Since the next space 18' is comparatively small there will be no danger of the wedging of the potatoes in this space in spite of the fact that the roller 13 is rotating more rapidly than the next succeeding roller 10'.

The "splitting" rollers 10' and 13 are all the same size and I prefer to cover them on the outside with any suitable surfacing, preferably of rubber or other resilient material, which surfacing may have short fingers or knobs as is customary with the roller surfacings found in many types of fruit and vegetable graders.

The potatoes, other than those which are oversize and which are to be graded, pass through the large space 18 between the "splitting" rollers and are delivered by suitable chutes (or belts) 20 on to the first row 19 of sizing rollers. The oversize potatoes are delivered from the "splitting" rollers over a discharge chute 46 to a conveyor 42.

The rollers in the sizing rows 19, 24, 26 and 27 are similar, the sizing rollers in one row differing from those in another row only in size. In the grader the size of the rollers is diminished in the successive downward rows.

Since the rollers in all the sizing rows are similar it will suffice to describe those of a single row. The shape of the sizing rollers is shown in Figure 4. The sizing rollers are spool-shaped, each roller having a series of cylindrical sections 43 of the same diameter with concave hour-glass sections 44 between the cylindrical sections. The rollers are set very close together, as shown in Figure 4, and the concave hour-glass sections 44 are substantially semi-circular in longitudinal section so that substantially circular passageways or spaces

21 are formed between the surface of adjacent rollers. The circular openings are of uniform diameter throughout the entire row but are of successively smaller diameter in the various rows of the sizing rollers. Consequently as the rollers in successive rows are made smaller with the diameters of the cylindrical sections 43 smaller, the circular passageways 21 in these rows will be correspondingly smaller and adapted for potatoes of smaller sizes.

The speed of the rollers in each sizing row increases from left to right (as viewed in Figure 1). Thus each roller is rotated more rapidly than the roller immediately preceding it. This increase in the speed of rotation of the rollers throughout the row prevents any wedging or damaging of the potatoes between the sizing rollers.

These spool-shaped sizing rollers may be constructed of various materials, including metal, and may or may not have a surfacing of rubber or of any other suitable covering. Due to the special shape of the rollers and to the progressively faster speed of rotation of the rollers in each row no bruising of the potatoes occurs during the sizing operation, even though the rollers are made of metal without any softer covering. The relatively smooth contact surfaces of the rollers and the rigid mounting of the rollers are factors in preventing any potatoes from becoming squeezed during the sizing process.

Chutes 25, similar to the chutes 20, deliver the potatoes which are small enough to pass through the openings 21 of one sizing row to the next lower sizing row. Discharge chutes 22, 28, 29 and 30 carry the potatoes which are sized according to the rollers in the rows 19, 24, 26 and 27 respectively to the conveyors 23, 31, 32 and 33 respectively. The under sized product, or very small potatoes, passing through the openings of the last sizer row 27, are delivered to a conveyor 34.

Each of the discharge chutes 22, 28, 29 and 30, is equipped with a trap door 35 which may be opened to cause the potatoes sorted by one row of rollers to be combined with those collected from the next lower row. In this manner two or more sizes can be combined in the "sizer" and the total number of sizes into which the pack is divided may be altered to meet requirements.

A similar trap door 35 may be placed in the chute 46 leading from the row of "splitting" rollers in case it should sometime be desired to mix some over-sized potatoes with some of the smaller sizes from the sizing rollers below.

Due to the means provided for adjusting the spacing in the first row of "splitting" rollers and to the means provided for combining the potatoes collected from each sizing row of rollers with those collected from one or more subsequent rows, a very flexible type of "sizer" is obtained which can easily be adjusted to meet the special conditions of a particular pack of potatoes and to comply with any special sizing requirements.

Although I consider that the most important use of my improved grader will be in connection with the grading or sizing of potatoes as described, nevertheless it will be obvious that the "sizer" can also be employed in the same manner for grading various vegetables, fruits and other materials. For smaller vegetables or fruits it might be necessary to change the sizing rollers and to substitute smaller rollers with smaller passageways or openings, and vice versa for larger products or materials, but further than this no changes would be necessary.

In the modified form of my "sizer," illustrated diagrammatically in Figures 6 and 7, the rows of sizing rollers instead of being arranged in spaced horizontal relation, one below the other, are all in the same horizontal plane. This arrangement would be more advantageous under some conditions. In Figures 6 and 7, B, C, D, and E indicate the groups or rows of sizing rollers and these correspond to the rows 21, 26, 24 and 19 respectively of Figure 1. In this modification of my "sizer" the order of the rows of sizing rollers is reversed and consequently the row of smallest sizing rollers B (corresponding to row 21 in Figure 1) is placed first, and the potatoes or other product or material to be sized will come into contact with this row after passing through the "splitting" rollers A. The smallest size, removed by the first row B passes through openings between the spool-shaped rollers to a suitable conveyor F. The larger sizes, which are too large to pass through the openings in the row B, move on to the next larger row C, and so on, there being corresponding suitable conveyors F', F² and F³ for the sizes sorted out by each sizing row.

In this arrangement however the "splitting" rollers A preferably have their axes normal to the axes of the sizing rollers, as indicated in Figures 6 and 7, and are located above the first or smallest sizing rollers B. The oversize potatoes, or other product, which are too large to pass between the "splitting" rollers, and thus too large for any minimum sizing, are delivered to a separate conveyor H corresponding to the conveyor 42 of Figure 1. Diversion gates (not shown) associated with the various conveyors can be used for mixing and combining the resultant sizes in any manner desired.

Various types of conveyors may be used to convey the sized potatoes or other product from the different sets of rollers. Thus the conveyors could be moving belts or chain sorting tables.

Further modifications in the structure of my "sizer" would be possible within the scope of my invention and it is not my intention to limit my invention otherwise than as set forth in the claims.

I claim:

1. A sizer of the character described comprising, a row of "splitting" rollers, said row composed of one set of spaced rollers journaled in fixed bearings and a second set of spaced rollers journaled in movable bearings, the rollers of both sets arranged alternately in said row, means interconnecting said movable bearings at each side of said row and means for moving said movable bearings at each side in unison, whereby to adjust the spacings between the alternate rollers in said row in the manner and for the purpose described, means for rotating the rollers in said first-mentioned set in unison, means for rotating the rollers in said second-mentioned set in unison at a different rate of speed from the rollers of said first-mentioned set, a plurality of tiers of "sizing" rollers arranged in consecutive spaced relation one below the other and located below said row of "splitting" rollers, the "sizing" rollers in said tiers being similar, those in the same tier being identical and those in one tier differing from those in another tier only in size, the size diminishing in the successive downward tiers, a conveyor leading from said "splitting" row, a conveyor associated with each of said tiers of "sizing" rollers, a discharge chute leading from each tier to such conveyor, and means in each

chute adapted, when operated, to cause material in the chute to drop through said chute instead of passing along the chute to the conveyor, whereby to combine the material sorted by two or more tiers.

2. A sizer comprising, a row of "splitting" rollers, said row composed of one set of spaced rollers journaled in fixed bearings and a second set of spaced rollers of the same size as those of the first-mentioned set and located in the same horizontal plane with the first-mentioned set journaled in movable bearings, the rollers of both sets arranged alternately in said row, a movable member at each side of said row, said 10 movable bearings connected with said members respectively, means for moving said movable members and therewith said second set of rollers in the plane of said row, whereby to adjust the spacings between the alternate rollers in said 15 row, means for rotating the rollers in said first-mentioned set in unison, and means for rotating the rollers in said second-mentioned set in unison in the same direction as and at a faster rate of speed than the rollers of said first-mentioned 20 set, a plurality of tiers of sizing rollers arranged in consecutive spaced horizontal relation one below the other and located below said row of "splitting" rollers, the sizing rollers in said tiers being similar, those in the same tier being identical 25 and those in one tier differing from those in another tier only in size, the size diminishing in the successive downward tiers, the rollers in each tier placed close together, said sizing rollers being spool-shaped and composed of series of 30 cylindrical sections with concave hour-glass sections there between, the concave surface of said hour-glass sections being substantially semi-circular in longitudinal section, the speed of rotation of said sizing rollers increasing consecutively 35 in each tier towards the discharge end of said tier, conveyors associated with said "splitting" row and with said tiers of sizing rollers respectively, a discharge chute leading to each conveyor, and a trap door in each chute adapted, when 40 operated, to cause material in the chute to drop through said chute instead of passing along the chute to the conveyor, whereby to combine sizes of material as desired.

3. A sizer of the character described including, 45 a row of "splitting" rollers composed of two sets of spaced rollers arranged in the same horizontal plane with their axes parallel, the rollers of said sets placed alternately in said row, the spacing between the rollers of each set being fixed but one set movable with respect to the other set whereby 50 to adjust the spacings between alternate rollers in said row, means for rotating the rollers in each set in unison and for rotating the rollers of one set faster than those of the other set, a row of 55 sizing rollers below said row of "splitting" rollers with their axes at right angles to the axes of the "splitting" rollers, said sizing rollers comprising a plurality of groups, the rollers in said groups being similar, those in the same group being identical 60 and those in one group differing from those in another group only in size, the group representing the smallest size being located directly below said "splitting" rollers and the other groups arranged consecutively in the order of increasing size, said sizing rollers all rotating in the same 65 direction, whereby the material which is too large to be removed by one group of sizing rollers will be caused to move on to the next group, said sizing 70 rollers being spool-shaped, and conveyors as- 75

sociated with said "splitting" rollers and with each group of sizing rollers respectively.

4. In a sizer of the character described, a row of "splitting" rollers composed of two sets of spaced rollers arranged in the same horizontal plane with their axes parallel, the rollers of said sets placed alternately in said row, the spacing between the rollers of each set being fixed but one set movable with respect to the other set whereby to permit adjustment of the spacings between alternate rollers in said row, means for rotating the rollers in each set in unison in a direction adapted to cause material to travel transversely over said rollers along said row, means for discharging material from the end of said row, and a row of sizing rollers located below said "splitting" rollers for sizing material dropped down between the "splitting" rollers.

5. In a sizer of the character described, a row of "splitting" rollers composed of two sets of spaced rollers arranged in the same horizontal plane with their axes parallel, the rollers of said sets placed alternately in said row, the spacing between the rollers of each set being fixed but one set movable with respect to the other set whereby to permit adjustment of the spacings between alternate rollers in said row, means for rotating the rollers in each set in unison in a direction

adapted to cause material to travel transversely over said rollers along said row and for rotating the rollers of one set faster than those of the other set for the purpose explained, means for discharging material from the end of said row, and a row of spool-shaped sizing rollers located below said "splitting" rollers for sizing material dropped down between the "splitting" rollers.

6. In a sizer of the character described, a row of "splitting" rollers composed of two sets of spaced rollers arranged in the same horizontal plane with their axes parallel, the rollers of said sets placed alternately in said row, the spacing between the rollers of each set being fixed but one set movable with respect to the other set whereby to permit adjustment of the spacings between alternate rollers in said row, means for rotating the rollers in each set in unison in a direction adapted to cause material to travel transversely over said rollers along said row and for rotating the rollers of one set faster than those of the other set for the purpose explained, means for discharging material from the end of said row, and a plurality of rows of sizing rollers located below said "splitting" rollers and arranged in tiers for sizing material dropped down between the "splitting" rollers.

FRED HODECKER.
